UNITED STATES PATENT OFFICE.

LOUIS DUNN, OF MINNEAPOLIS, MINNESOTA.

SYRINGE ATTACHMENT.

1,373,803.

Specification of Letters Patent.

Patented Apr. 5, 1921.

Application filed March 1, 1919. Serial No. 280,084.

To all whom it may concern:

Be it known that I, LOUIS DUNN, a citizen of the United States, resident of Minneapolis, county of Hennepin, State of Minnesota, have invented certain new and useful 5 Improvements in Syringe Attachments, of which the following is a specification.

In surgical operations, when a local anesthetic is applied, difficulty is frequently experienced with the syringes in general use, 10 if the operation is one requiring the injection of a considerable quantity of anesthetic fluid, owing to the fact that the needle through which the fluid is discharged into 15 the tissues will frequently have to be removed or the syringe detached therefrom for the purpose of refilling the syringe. The removal of the needle from the tissues not only involves loss of time, but there is always 20 danger that the point of the needle may become contaminated during the re-filling of the syringe and the re-insertion of the needle into the tissues. Devices, including 25 syringes of special construction, have been made for delivering a continuous supply to the needle, but these are more or less objectionable, owing to the fact that an ordinary syringe can not be employed with them, and the specially constructed syringes have 30 so many tortuous passages and valves that it is difficult to keep them clean and ready for use.

One of the principal objects therefore, of my invention, is to provide a syringe which 35 will permit the injection into the tissues of the full amount of anesthetic fluid desired without the necessity of removing the needle or detaching the syringe for re-filling purposes.

40 A further object is to provide a syringe attachment which can be applied easily and quickly to a standard syringe and needle without any special adaptation or change in construction.

45 A further object is to provide a syringe of this type with a glass or transparent barrel, whereby if the operator gets the point of the needle into a vein, this fact will be shown by blood entering the barrel when the 50 syringe piston is drawn back.

A further object is to provide a syringe attachment of simple construction which can be easily kept clean and may be readily taken apart for examination or repairs.

55 A further object of the invention is to

provide against the injection of air bubbles, etc., into the veins of the patient.

The invention consists generally in various constructions and combinations, all as hereinafter described and particularly pointed out in the claims.

In the accompanying drawings forming part of this specification,

Figure 1 is a view, showing my invention applied to a needle and syringe, ready for use,

Fig. 2 is an enlarged sectional view through the attachment, showing the passages therein and the check valve for preventing flow of the fluid back to the receptacle,

Fig. 3 is a detail enlarged view, showing the manner of inserting the point of the needle under the skin, or into the tissues of the patient,

Fig. 4 is a detail enlarged view of the point of the needle.

In the drawing, 2 represents the barrel of a syringe, preferably formed of glass or transparent material, such as is in general use in surgical work. 3 is a glass plunger, having a ground joint with the barrel but mounted to slide freely therein to fill the barrel or eject the fluid therefrom. 4 is a finger grip device, preferably mounted on the barrel for convenience in holding it when in use. 5 is an ordinary hypodermic needle having a passage 6 therein with a comparatively sharp point 7 which is inserted under the skin or into the tissue to deliver the desired quantity of anesthetic fluid at the point desired. This needle is preferably of the type in general use, provided with an end 8 having a tapered socket therein adapted to receive the syringe nozzle when mounted directly thereon. When the needle is so mounted and the contents of the syringe barrel discharged, it is necessary to remove the needle from the tissues and insert it into the fluid or detach the syringe from the needle to refill the syringe. My invention eliminates entirely the necessity of such removal or detachment and all danger of infection through contact of the point of the needle with the fingers of the operator or with some foreign substance.

In carrying out my invention, I provide a head 10 having a plug 11 in one end thereof provided with a tapered socket 12 to receive the tapered end of the syringe nozzle 9,

These parts will fit snugly together and be held by their frictional engagement from accidental separation, but may be easily and quickly pulled apart when the use of the 5 syringe is completed or for any other purpose. These tapered surfaces may be threaded, if preferred, such being an equivalent construction.

The head 10 is provided with a chamber 10 13 with which the syringe nozzle communicates through the plug 11, a nipple 14 is fitted into the other end of the head 10 and communicates with the chamber 13 and said head and has a tapered outer end 16 15 which fits into the tapered socket in the end 8 of the needle and is held therein by frictional engagement. The head 10 has a passage 17 leading from the chamber 13 to a socket 18, the walls of which are preferably 20 interiorly threaded to receive a coupling 19 having an end 20 for connection with a section of hose 21. A valve seat 22 is formed in the end of the coupling and a check valve 23 is provided in said coupling to allow the 25 liquid to flow through the coupling to the chamber 13 and to prevent the return of the liquid from said chamber. One end of the hose section 21 is adapted to be inserted 30 into a bottle or other receptacle 24 containing a suitable fluid, and a weight 25 is preferably provided on the open end of the hose section to hold it at the bottom of the fluid receptacle.

In using the device, the head 10 is interposed between the standard syringe and standard needle and the needle inserted into the fluid and the plunger operated until the barrel of the syringe is filled. The pointed end of the needle is then inserted through 35 the skin or in the tissues, as usual with hypodermic needles. Then the needle is pushed through the tissues to be anesthetized and at the same time the plunger is operated to discharge the fluid. When the 40 syringe is empty, the retraction of the plunger will immediately fill it from the supply receptacle through the hose 21, the needle being left in the tissues and the discharge port in the end of the needle being 45 closed by the tissues so that the injected fluid cannot flow back to the syringe and interfere with the refilling of the syringe barrel from the fluid receptacle. As soon as the 50 syringe has been refilled, the discharging 55 operation may be resumed, the needle being moved in the same direction or in a different direction through the tissues and the operation of discharging and refilling the syringe continued until the desired amount of anesthetic fluid has been used. In this way I not 60 only save considerable time in preparing the patient for an operation, but avoid the added danger of infecting the patient by repeated insertion of the needle. With my 65 attachment only one puncture is necessary,

the needle point being kept embedded and moved about in the tissues as long as it is necessary or desirable to obtain the desired anesthetic effect. The attachment is so constructed that it can be used very readily 70 with different sizes and styles of syringes and needles, the taper of the syringe nozzle socket and the taper of the nipple to enter the socket in the needle adapting the device for variations in size. When the work has 75 been completed, the syringe and needle can be easily and quickly detached from the head and the parts may then be easily sterilized and made ready for further use.

By employing a syringe barrel formed of 80 glass or transparent material, the operator can see that the fluid he is about to inject into the body of the patient is free from air bubbles, and if it happens that the point of the needle has been inserted into a blood vessel 85 when the piston is withdrawn blood will enter the glass syringe barrel and be observable by the operator. This will demonstrate to him that the point of the needle is in a blood vessel, and will warn him to either 90 push the needle point farther into the tissues or to withdraw it from the blood vessel. In this way the introduction of the anesthetic fluid into the blood current directly will be avoided.

It will be seen, therefore, that this attachment is particularly valuable for use in connection with syringes having glass or transparent barrels, although I do not limit myself to barrels formed of such material.

While the syringe herein described is particularly adapted for applying local anesthetics in surgical work, I do not limit myself to any particular purpose for this syringe, but the same may be employed 105 wherever it is desired to inject material hypodermically, or into any of the tissues of a patient.

I claim as my invention:

1. The combination, with a syringe and 110 a needle having a passage therethrough and a point for insertion in to the tissues, of a head having means for mounting the syringe nozzle and the shank of the needle therein, a passage being provided between 115 said nozzle and needle through said head, a tube having one end for insertion into a fluid and connected at its other end with said head and means for closing the passage through said tube to said head when 120 the syringe plunger is projected and opening said passage when the plunger is retracted, and said syringe having a transparent barrel through the walls of which the fluid in the syringe is visible and its condition may be determined without withdrawing the needle from the tissues.

2. The combination, with a syringe having 125 a transparent barrel and hypodermic needle, of a tube communicating at one end 130

with a source of fluid supply and provided with means at its other end for mounting the nozzle of the syringe barrel and the needle therein, a normally unobstructed 5 passage being provided between said syringe nozzle and said needle, means mounted to open the passage between said fluid supply and said syringe when the syringe is operated, the transparent syringe barrel 10 enabling the user to determine the condition of the fluid and the position of the needle in the tissues.

3. The combination with a syringe and a head, one of the parts being transparent, a 15 needle, all rigidly but detachably connected, the head having a chamber therein extending above the needle and syringe connections and having an unobstructed passage therethrough whereby the syringe may 20 serve as a handle for the insertion of the needle into tissue, the upper part of the chamber may serve as a trap for air bubbles and the parts may be readily separated for cleaning, and a tube having one end 25 for insertion into a fluid and connected at its other end with said head, and a valve which opens and closes when the syringe is operated.

4. The combination with a rigid trans- 30 parent syringe, a head and a needle, rigidly but detachably connected and having an unobstructed passage therethrough whereby the syringe may serve as a handle for the insertion of the needle into tissue and the 35 parts may be readily separated for cleaning, and a tube having one end for insertion into a fluid and connected at its other end with said head, and a valve which opens when the syringe plunger is retracted 40 and closes when it is advanced, whereby the material in the syringe may be inspected and the syringe repeatedly operated without withdrawing it from the tissue.

5. The combination, with a syringe and 45 a needle having a passage therethrough and a point for insertion into the tissues, of a head having sockets therein to receive the syringe nozzle and the shank of said needle there being an unobstructed commu- 50 nicating passage between said syringe and needle, said head having a coupling and a check valve therein and a port leading from said valve to said syringe and needle, a tube mounted on said coupling and having 55 an end for insertion into a fluid, the re- traction of said plunger when the point of said needle is closed opening said check valve automatically and filling the syringe from said fluid supply and the projection of said 60 plunger closing said valve and discharging

the fluid through said unobstructed passage to said needle.

6. The combination with a syringe hav- 65 ing a nozzle thereon, of a head having a socket to receive said nozzle and a cham- 70 ber in said head communicating with the passage through said nozzle, a coupling mounted on one side of said head and hav- 75 ing a passage therethrough leading to said chamber and a flexible hose leading from 80 said coupling to a source of liquid supply, a nipple mounted in said head and fitting the socket in a hypodermic needle and hav- 85 ing a passage therethrough communicating with the chamber in said head, the nipple 90 of said head, when inserted into the socket of the needle, forming a close joint there- 95 with, a valve mounted in said coupling and normally closing the passage therethrough, said valve being mounted to open when 100 suction is applied to said chamber by the retraction of said syringe plunger to fill said syringe with liquid, the retraction of the plunger after the needle has been inserted into the tissues operating to open 105 said valve and fill said syringe and the for- 110 ward movement of said plunger operating to close said valve and project the liquid in the syringe through the passage in said nipple.

7. The combination, with a syringe and 115 needle having a passage therethrough and a point for insertion into the tissues, of a head, a chamber formed in the head and having openings extending from the cham- 120 ber through the head and providing oppo- 125 sitely disposed sockets extending from be- 130 low the top of the chamber to receive the syringe nozzle and the shank of the needle whereby air bubbles may be trapped in the 135 upper part of the chamber, there being an unobstructed communicating passage be- 140 tween the syringe and needle point, means 145 providing communication between said pas- 150 sage and a fluid source and an automatic 155 check valve interposed in said communicat- 160 ing means to permit the fluid to pass only in a direction from said source to 165 said passage, whereby when the needle 170 point is closed by insertion into the tissues, 175 retraction of the syringe plunger automatic- 180 ally opens the check valve and fills the 185 syringe from the fluid source and projec- 190 tion of the plunger automatically closes the 195 valve and forces the fluid through said un- 200 obstructed passage into the tissues.

In witness whereof, I have hereunto set my hand this 23d day of February, 1919.

LOUIS DUNN, M. D.
